HARRY K. REINOEHL, OF SPRINGFIELD, OHIO

VALVE-OPERATING MECHANISM FOR INTERNAL-COMBUSTION ENGINES

Application filed May 11, 1928. Serial No. 277,034.

This invention relates to improvements in valve actuating mechanism for internal combustion engines, it more particularly relating to that class of engines having a single cylindrical sleeve valve to which a combined reciprocatory and oscillatory motion is given for the purpose of performing the valve functions.

An object of the invention is to provide a simple, durable and inexpensive mechanism for the work of actuating the valve, transmitting the motion received from a suitable source of power.

A further object of the invention is to provide a valve operating mechanism of the character described which is devoid of gearing to thereby eliminate the wear incidental to gear operated mechanism.

A further object is to provide operating devices for the valve and connection with the valve that are arranged entirely at the side of the engine with consequent advantages in construction.

Other objects and advantages will appear from an inspection of the accompanying drawings and from the following description and specifications.

In the drawings:

Fig. 1 is a section on line 1—1—1 of Fig. 2.

Fig. 2 is a vertical section on the line 2—2 of Fig. 1.

Fig. 3 is a plan view, partly in section, similar to Fig. 1, but with the parts in a different working position.

Fig. 4 is a plan view similar to Figs. 1 and 3 with the parts in a different working position.

Fig. 5 is a vertical section on the line 5—5 of Fig. 2.

Fig. 6 is a plan view of a modification of my invention.

Fig. 7 is a section on the line 7—7 of Fig. 6.

Fig. 8 is a plan view of another modification.

Fig. 9 is a front elevation partly broken away and shown in section.

As is customary in engines of the four cycle single sleeve valve type, ports A and B, in the cylinder walls, the one for the admission of air or mixture, and the other for the pas-

sage of exhaust gases, are successively uncovered or opened in proper sequence, with suitable alternate intervals when all the ports are covered or closed. To accomplish this, the valve is given an oscillating and reciprocating motion, so timed that for substantially the duration of one main crankshaft revolution, the ports P in the valve are remote from either group, and at other times are in registry with one or the other of the groups of ports in the walls of the cylinder.

Referring to the drawings, in which is shown enough of a sleeve valve, cylinder and other appurtenances to illustrate the manner in which my invention is incorporated therein, 1 is the sleeve valve of a conventional type rotatably and slidably mounted in a cylinder 2 surrounded by the usual water jacket 3. At the lower end of one of the outer sides of the valve 1 is a threaded integral boss 4 having a transverse slot 5, into which an externally threaded plug 6, having a transverse bore 7, is inserted, this plug being capable of oscillatory movement relatively to the boss.

Adjacent and parallel to the cylinder 2 is a cylindrical guide way 8 adapted to receive a guide member 9, slidably and rotatably mounted therein, this member 9 having at its lower end an integral trunnion or pin 10 which is loosely inserted in the bore 7 of the plug 6, so as to be capable of a reciprocating motion in the plug.

Provision is made for universally connecting this guide member with the crank pin of a rotary shaft. Formed integrally with the guide member is an arm 11 which carries a half-bearing portion 12 with ears 13 through which screws 14 for the retention of a bearing cap 15 are passed. The bearing portion 12 and the cap 15 are finished to a spherical contour to receive a split spherical bushing the parts of which are indicated as at 16, 16, the bushing parts having a straight bore adapted to have a slidable and rotatable engagement with a crank-pin 18 formed in a shaft 19, which is mounted preferably in longitudinally parallel relation to the main crank shaft, indicated in dotted line at S, being carried in bushings 20 pressed in down-

wardly extending bosses 21 formed in the main engine housing 22, and deriving its motion from the main crank-shaft through the medium of suitable gearing (not shown).

5 In operation, as the shaft 19 revolves by reason of its geared connection with the main shaft (in this case, at half engine speed), the sleeve valve is lifted and oscillated, and then lowered and again oscillated, the two 10 oscillatory movements, however, being unlike; that is to say, as the valve rises the oscillation is such as to bring the valve port in one part of the cylinder and as the valve lowers the oscillation is such as to bring the valve 15 port in another part of the cylinder. By proper positioning of the ports in the valve itself, and in the walls of the cylinder, the events of the cycle are carried out. Referring to Fig. 3, the sleeve valve crank 18 is 20 shown at about the mid-point in the vertical stroke of the parts connected therewith, while at the same time the parts are at an extremity of the arc of oscillation about their respective center lines. As the sleeve shaft 19 is 25 revolved in the direction of the arrow thereon, the crank-pin 18 for an individual valve will assume successively higher positions, carrying the entire mechanism upwardly and at the same time turning the valve about its 30 axis C. The related direction of movements are shown by small arrows on the parts themselves, and continued rotation brings the parts to the position as shown in Figs. 1, 2 and 5, wherein the crank-pin 18 has reached 35 the upper dead center, the valve 1 is at the point of its uppermost travel, and at the center of the arc of its oscillation.

In Fig. 4, the shaft 19 has made one half turn as compared to Fig. 3, bringing the 40 valve 1 again to substantially the same point as in Fig. 3, but at the other extremity of its arc of oscillation about its center C.

A modification of the invention is shown in Figs. 6 and 7 in which the guide member 45 9' has, at its lower end, a transversely extending boss 24 into which the shank 25 of a connecting rod 26 is slidably fitted. At the lower end of the valve 1' are integral bosses 4', 4', each having a transverse slot 5', while 50 in the end of the connecting rod a pin 27 is fitted and retained by a cotter 28, this pin being journaled in the boss 4'.

A further modification is shown in Figs. 8 and 9 in which the boss 4" at the lower end 55 of the valve 1" has a transverse slot 5"; a spherical seat machined in the boss receives a ball 29 which is slidably engaged with the trunnion pin 10; a socket member 30 completing the seat is pressed into the opening 60 31.

By this construction it will be seen that I am enabled to provide a valve-actuating mechanism with few moving parts, and one in which the operating shaft is rotated at 65 half engine speed, with a consequent reduc-

tion in wear and deterioration. With suitable proportioning of lever arms and positioning of centers or pivotal points, the destructive effects of the inertia forces set up by the reciprocatory movements, while not eliminated, are materially reduced, since a force set up in any direction is at once influenced by a second force acting in a direction at substantially right angles. It will also be further noted that all gearing, such as worms and worm wheels, is eliminated in the operating devices, with a consequent reduction in wear and advantage in adjustments to take up for wear.

This arrangement also enables me to arrange all of the valve operating mechanism at one side of the engine, with the valve sleeve bosses projecting laterally, which enables me to use the conventional crank-case construction with a strengthening rib between each cylinder and also permits close spacing of the cylinder bores.

Having thus described my invention, I claim:

1. In a valve mechanism of the character described, a cylinder, a sleeve valve in said cylinder mounted for reciprocatory and oscillatory movements, a rotatable crank pin, and means for connecting said sleeve to said crank pin including an intermediate crank arm mounted for reciprocatory and oscillatory movements together with means for universally connecting said crank arm with said crank pin.

2. In a valve mechanism of the character described, a cylinder, a sleeve valve in said cylinder mounted for reciprocatory and oscillatory movements, a rotatable crank pin, means for connecting said sleeve to said crank pin including a guide mounted intermediately between said sleeve and crank pin for reciprocatory and oscillatory movements, a crank arm connected with said guide, and means for universally connecting said crank arm with said crank pin.

3. In a valve mechanism of the character described, a cylinder, a sleeve valve in said cylinder mounted for reciprocatory and oscillatory movements, a rotatable crank pin, a guide mounted intermediately between said sleeve and crank pin in parallel relation with said sleeve for reciprocatory and oscillatory movements, means for connecting said guide with said sleeve to cause said sleeve to move therewith, a crank arm connected with said guide, and means for universally connecting said crank arm with said crank pin.

4. In a valve mechanism of the character described, a cylinder, a sleeve valve in said cylinder mounted for reciprocatory and oscillatory movements, a rotatable crank pin, a guide mounted intermediately between said sleeve and crank pin for reciprocatory and oscillatory movements in parallel relation with said sleeve, a connection between said

guide and sleeve arranged to allow relative reciprocatory and oscillatory movement of its parts, and means for universally connecting said sleeve with said crank pin.

5. In a valve mechanism of the character described, a cylinder, a sleeve valve in said cylinder mounted for reciprocatory and oscillatory movements, a rotatable crank pin, a guide mounted intermediately between said sleeve and crank pin for reciprocatory and oscillatory movements in parallel relation with said sleeve, a connection between said guide and sleeve arranged to allow relative reciprocatory and oscillatory movement of its parts, and a crank arm rigidly connected with said guide and having a universal connection with said crank pin.

6. In a valve mechanism of the character described, a vertical cylinder open at its lower end, a main longitudinally extending crank shaft beneath said cylinder, a sleeve valve in said cylinder mounted for reciprocatory and oscillatory movements, a second shaft having a crank pin arranged parallel with said main crank shaft and extending in a plane near and at one side of the lower end of said cylinder, and devices other than gears between said sleeve and crank pin constructed and arranged so that rotary movements of said crank pin impart oscillatory and reciprocatory movements to said sleeve.

7. In a valve mechanism of the character described, a cylinder, a sleeve valve in said cylinder mounted for reciprocatory and oscillatory movements, a revoluble crank pin whose axis is parallel to the longitudinal axis of the main crank shaft of the engine and which is at all times tangential to a circle whose center is the center of the cylinder and whose diameter is larger than the diameter of the cylinder, and devices between said sleeve and crank pin constructed and arranged that rotary movements of said crank pin impart oscillatory and reciprocatory movements to said sleeve, said devices including a universal connection and being located entirely on an outer side of said cylinder.

8. In a valve mechanism of the character described, a cylinder, a sleeve valve in said cylinder mounted for reciprocatory and oscillatory movements, a revoluble crank pin whose axis is parallel to the longitudinal axis of the main crank shaft of the engine and which is at all times tangential to a circle whose center is the center of the cylinder and whose diameter is larger than the diameter of the cylinder, and devices between said sleeve and crank pin constructed and arranged that rotary movements of said crank pin impart oscillatory and reciprocatory movements to said sleeve, said devices including a universal connection directly associated with said crank pin.

9. In a valve mechanism of the character described, a cylinder, a sleeve valve in said

cylinder mounted for reciprocatory and oscillatory movements, a rotatable crank pin whose axis is parallel to the longitudinal axis of the main crank shaft of the engine and which is at all times tangential to a circle whose center is the center of the cylinder and whose diameter is larger than the diameter of the cylinder, and devices for connecting said sleeve to said crank pin including a spherical shaped bearing between said crank pin and the part of said devices which is connected therewith.

In testimony whereof, I have hereunto set my hand this 5th day of May, 1928.

HARRY K. REINOEHL.
